UNITED STATES PATENT OFFICE.

JOSEPH A. WARREN, OF DETROIT, MICHIGAN.

ORGAN-CASE.

SPECIFICATION forming part of Letters Patent No. 295,214, dated March 18, 1884.

Application filed April 27, 1883. (No model.)

To all whom it may concern:

Be it known that I, JOSEPH A. WARREN, of Detroit, county of Wayne, State of Michigan, have invented a new and useful Improvement 5 in Organ-Cases; and I declare the following to be a full, clear, and exact description of the same, such as will enable others skilled in the art to which it pertains to make and use it, reference being had to the accompanying drawings, which form a part of this specification.

My invention consists in the combination of devices and appliances hereinafter specified, and more particularly pointed out in the claims.

In the drawings, Figure 1 is a perspective 15 view of the lower portion of a reed-organ case, showing my improved self-closing pedals. Fig. 2 is a perspective of the upper portion of the case.

In carrying out my invention as shown in 20 the drawings, A represents a reed-organ case.

A' represents ordinary self-closing pedals.

A² represents the brackets at the sides of the 25 pedals.

a is a strap connecting the pedals with the bellows.

a' represents my improved flange or protector, extending across the full width of the 30 pedal. This flange is so constructed as to close up suitably in contact with the case whenever the pedals are relaxed, so as to effectually seal 35 the case from the entrance of mice or vermin, and may be made of any suitable shape to secure this result.

It is evident that the pedals and the brackets 35 may be brought forward, so that the inner edges of the pedals will be even with the edge of the case when closed. I prefer, however, not to bring the brackets and pedals out so far, but to provide the case with blocks a², projecting 40 inward from the case, as shown in Fig. 1, whereby the inner edge of the case is effectually closed at the upper corners of the pedals when constructed to extend partially within the case.

45 It is evident that the inexpensive flange a' answers at the same time as a "strap-protector," while it thoroughly protects the interior mechanism of the organ from injury, the bottom of the case being covered with wire-cloth.

B is a sliding panel, adapted to be adjusted up or down over the inclosure C.

A³ and A⁴ are portions of the frame forming the sides of said inclosure.

C' is a rock-shaft extending from side to side 55 of the inclosure C, and having its bearings in the side pieces, D and D', said shaft provided with arms c and c', said arms engaged at their outer ends with the upper portion of the sliding panel, the construction being such that 60 when said arms of the rock-shaft C' are thrown upward in an upright position the sliding panel will be drawn up, forming the front of the inclosure C, and when said arms are thrown down toward the base of said inclosure the 65 sliding panel will be forced downward into a suitable position for use as a writing-desk.

The arms of the rock-shaft may be located outside or upon the inside of the side pieces, A³ and A⁴—preferably upon the inside, out of 70 view.

The inclosure may be divided into drawers, pigeon-holes, or shelves, as may be desired, arranged in any suitable manner, in which case the arms of the rock-shaft will work in the 75 spaces a² upon each side of the inclosure.

It is evident that when the sliding panel is adjusted up into place to form the front of the inclosure C it may in that position act as a book-rack.

It will be seen that but one face of the panel is presented to view whatever may be its position, dispensing with the necessity of putting a finish on both sides of the panel, as is required where the panel is hinged to the case 85 so as to be turned down, and where the two surfaces of the panel must be alternately exposed to view as the panel is turned up and down.

It is evident that the arms c and c' may be suitably pivoted at their rear ends in the frame 90 without having the rock-shaft C' extending from side to side of the inclosure. I would have it understood that I contemplate such a construction.

What I claim is—

1. The combination, with an organ-case and self-closing pedals, of a sealing-flange secured to said pedals, adapted to suitably close the space between said pedals and said case, substantially as described.

2. The combination, with an organ-case and self-closing pedals, of a sealing-flange secured to said pedals and suitable blocks, a², secured to said case, said flange and blocks adapted to

suitably close the space between said pedals and said case, substantially as described.

3. The combination, with an organ-case, of a sliding panel and a rock-shaft connected with 5 said panel, whereby the panel may be slid downward for use as a writing-desk or be slid upward out of the way, substantially as described.

4. The combination, with an organ-case and 10 a rock-shaft having its bearings therein, and provided with arms c and c' , of a sliding panel secured at its upper end to the extremities of the said arms, and adapted to be slid upward against the case or be slid downward for use 15 as a writing-desk, substantially as described.

5. The combination, with an organ-case provided with the side pieces, $A^3 A^4$, of a rock-shaft, having end bearings therein and provided with arms $c c'$, and a sliding panel se-

cured at its upper end to the extremities of 2 the said arms, and adapted to be slid downward for use as a writing-desk or slid upward against the case, substantially as described.

6. The combination, with an organ-case having an inclosure, C , of a rock-shaft and a sliding panel connected therewith, and adapted to slide upward to cover the inclosure, and thus serve as a book-rack, or slide downward for use as a writing-desk, one surface only of the panel being exposed to view in either adjusted position, substantially as described.

In testimony whereof I sign this specification in the presence of two witnesses.

JOSEPH A. WARREN.
